TO THE WARNER & SWASEY COMPANY, OF CLEVELAND, OHIO, A CORPORATION OF
OHIO

CHUCK OPERATING MECHANISM FOR MACHINE TOOLS

Application filed April 10, 1928. Serial No. 268,911.

This invention relates to power operated mechanism for closing and opening chucks which are adapted to grip work pieces while the same are being machined. The present 5 invention, while applicable to chucks generally, has particular advantages in connection with large chucks, the closing and opening of which require a great amount of power and which can be closed and opened manually 10 only with great difficulty and with a considerable loss of time.

The principal object of the present invention is to provide a power operated chuck closing mechanism by which the chuck may 15 be closed and opened quickly and safely.

A further object is to provide a mechanism of this character by which the movement of the chuck operating member, whether in the form of a wrench or pinion, into and out of 20 engagement with the chuck as well as the rotation of this member are controlled by a single controlling lever which is capable of movements of different kinds or in different directions to effect successively, first, the engagement of the member with the chuck and 25 then its rotation in the closing or opening operation and then the stopping of this member and the withdrawal of it from the chuck.

A further object is to provide an effective 30 form of interlock between the controlling lever above referred to and the controlling lever for the chuck rotating mechanism so that it will be impossible either to engage the rotary endwise movable chuck opening and 35 closing member with the chuck while the latter is in rotation and also impossible to start the chuck into rotation while it is engaged with said member.

An additional object is to provide a control 40 mechanism for the chuck closing and opening member, this mechanism being so arranged and constructed that it will be impossible to start the rotation of this member until it is in full engagement with the part 45 or parts of the chuck which the member is adapted to engage and actuate.

Still further the invention aims to provide 50 an automatic brake for the chuck with an operative connection between it and the control lever for the chuck rotating mechanism such that a brake is released when the

control lever is moved from its neutral or inoperative position in either direction to operative position controlling the rotation of the chuck in one direction or the other, and, further, so that the brake is automatically applied when the control lever is moved from either of its operative positions to or toward neutral position. 55

Still further the invention aims to provide an effective combination between the control lever for the chuck driving mechanism, the control lever for the chuck closing and opening mechanism and this brake by which the interlock between the two levers is obtained and by which the brake is released or 60 automatically applied when the control lever for the chuck driving mechanism is shifted. 65

The above and other objects are attained by the present invention which may be here briefly summarized as consisting in certain 70 novel combinations and arrangements of parts and details of construction which will be described in the specification and set forth in the appended claims.

In the accompanying sheets of drawings 75 we have shown one embodiment of the invention wherein the mechanism involved in the invention is in the form of an attachment to the headstock and bed of a lathe, the power for operating the chuck closing and opening member being obtained from the headstock and in this instance being connected to one of the gears utilized in rotating the work spindle and chuck. However, the invention may be used to advantage on other types of 80 machine tools and is not necessarily connected to or operated by the power means for rotating the work spindle, nor is it necessary that the mechanism be in the form of an attachment to a machine tool as it may be built 85 into the same so as to form an integral or permanent part thereof. 90

In the accompanying sheets of drawings, Fig. 1 is a side elevation of the head and chuck to which the mechanism is applied and showing a portion of the bed; Fig. 2 is a view of the same looking toward the front of the chuck, the bed being in section; Fig. 3 is a plan view of the mechanism shown in Fig. 1; Fig. 4 is a view partly in elevation but prin- 95 100

cipally in section along the line 4—4 of Fig. 3; Fig. 5 is a view of the machine and mechanism shown in the preceding views but looking toward the head from the rear side of the machine, parts being in elevation but the major portion in section along the line 5—5 of Fig. 3; Fig. 6 is a fragmentary sectional view substantially along the line 6—6 of Fig. 4; Fig. 7 is a similar view showing a modification in the form of the chuck and in the chuck closing and opening member; Fig. 8 is a view partly in plan and partly in horizontal section showing detached the control mechanism for the chuck operating member; Fig. 9 is a side elevation of the same with parts in section, the main control lever being in one of its operative positions and thereby preventing the actuation of the control mechanism for the chuck closing and opening member; Fig. 10 is a view looking toward the left of Fig. 8 with parts in section and showing another portion of the attachment not shown in Fig. 8; Fig. 11 is a fragmentary view of a part of the control mechanism illustrated in Fig. 9 to show the parts in a different position than in Fig. 9, this view showing the main control lever in its central or neutral position, permitting the operation of the control mechanism for the chuck closing and opening device; Fig. 12 is an enlarged plan view showing a portion of the mechanism illustrated in Fig. 8, this view indicating by full lines and by dotted lines several positions of a pin forming a part of the control mechanism for the chuck closing and opening member; Fig. 13 is a view showing the support for the main control lever and certain portions which it operates, this view looking toward the head of the machine with the parts in front of it removed and showing a part in section; and Fig. 14 is a diagrammatic view illustrating particularly the mechanism by which the power is derived from the headstock to rotate in either direction the chuck closing and opening member.

Referring now to the drawings, we have shown at 20 a portion of the bed of a lathe at the head end of which is mounted the headstock which may be of usual or any suitable construction and is here designated generally by the reference character 21. The headstock is provided with a rotary work spindle 22 to the forward end of which is applied a work holding chuck 23 adapted to support the work while it is being machined.

The work holding member need not be in the form of what is generally known as a chuck, but for the sake of brevity and convenience of description, throughout the specification, it will be referred to as a chuck. Generally, however, the work holding member is in the form of a chuck which may be of standard form or it may be a special chuck for gripping work pieces. In either event,

it generally has work gripping jaws which are radially movable.

Regardless of whether a special or standard form of chuck is employed, the body of the chuck is preferably surrounded by a stiff annulus 24 which may be in the form of a casting, which is preferably supported on and clamped to the ways of the bed, as best shown in Fig. 2. This annulus forms a support for the major portion of the mechanism constituting the present invention.

In Fig. 6 wherein we have shown a special form of chuck, the inner part of the annulus 24 is arranged closely between two flanges 25 of the chuck body, there being a slight clearance between the inner periphery of the annulus and the corresponding surface of the chuck body, the chuck having no supporting relation in so far as the annulus is concerned.

This chuck, which is well adapted for supporting work pieces in the form of pipe coupling blanks, has two sets of jaws or work engaging members 26, one in advance of the other, which jaws are moved by two sets of wedges 27 which are shiftable axially in opposite directions by two scrolls 28 provided on their adjacent faces with gear teeth adapted to be engaged by a chuck closing and opening gear 29 so as to be simultaneously rotated in opposite directions, this gear 29 being

fixed to a part of a rotary and endwise movable shaft 30, the endwise movement moving the gear 29 into and out of engagement with the scrolls. When the shaft 30 and the gear 29 are in the positions shown in Fig. 6, these parts are in their normal, inoperative positions, the gear then being clear of the scrolls and chuck body so that the latter may be rotated without interference by the gear.

It will be understood that each set of jaws 26 is moved by one set of wedges adapted to be shifted by one of the scrolls, one set of wedges being adapted to slide in one direction, while the other set of wedges is adapted to slide in the opposite direction, the two sets being moved in opposite directions by the two oppositely rotated scrolls, as more fully described in a prior application Serial No. 229, 896, filed October 31, 1927.

In Fig. 7 we have shown a standard form of chuck wherein the chuck body 23a has one set of radially movable jaws 26a which are moved in the well-known manner by a scroll indicated at 28a, this scroll being rotated by any one of a series of pinions 28b, arranged

an equal distance apart about the periphery of the chuck body. Each pinion has a squared socket adapted to be engaged by the chuck operating member here in the form of a wrench 29a which is carried by the rotary and endwise movable shafts 30a similar to that shown in Fig. 6. The wrench 29a is shown in Fig. 7 withdrawn from the pinion 28b so that the chuck is free to rotate without interference by the wrench.

The constructions shown in Figs. 6 and 7 are merely illustrative of many chucks which may be employed with the mechanism constituting the subject matter of the present invention.

The work spindle 22 and, therefore, the chuck are adapted to be rotated by a train of mechanism contained in the housing 31 of the headstock and this mechanism may be driven by any suitable source of power such as a motor or a belt pulley 32, indicated in Fig. 14, which may be rotated at a constant speed not only to operate the work spindle but also to actuate the tool carrying members which will be supported on the bed in the usual or well-known manner.

The endwise and rotatable shaft 30 which carries the chuck closing and opening member, such as the gear 29 or the wrench 29a, is in this instance arranged laterally of the chuck and substantially horizontally on the rear side of the chuck or on the rear side of the lathe, assuming that the chuck is applied to the work spindle of a lathe. This arrangement of the shaft and of the mechanism for actuating it on the rear side of the machine rather than on the front or on the top of the machine has the important advantage that it leaves the front and the top portions of the machine substantially clear of this mechanism so that it does not interfere with other working parts of the machine, such as a motor or other attachments.

The shaft 30 carrying the chuck operating member is supported along with other mechanism in a casing 33 which is bolted to a pad on the rear side of the annulus 24 as very clearly illustrated in Figs. 2 and 4. This shaft is adapted to be shifted in an endwise direction by mechanism to be referred to presently and it is adapted to be rotated in both directions, one direction of rotation being for shifting the jaws or work gripping means into engagement with the work piece and the other for shifting the work gripping means in the opposite direction away from the work piece. In this instance, the power for rotating the shaft 30 is derived from a gear 34 (see Figs. 13 and 14), forming one of the spindle driving gears of the headstock, this being a constant speed gear which is rotated as long as the pulley 32 is rotated or as long as the equivalent of the pulley such as the motor is in operation. That is to say, the rotation of the gear 34 is unaffected by the stopping of the work spindle, which is controlled by a clutch arranged at a suitable point between this gear and the work spindle. In this instance, power is taken from this gear through the rear side of the headstock to which is applied a casing 35 supporting two gears 36 and 37, (see Figs. 5, 13 and 14), the latter being an idler gear arranged between the gears 34 and 36. The gear 36 is mounted on a shaft 38 one end of which is

supported in the casing 35 which is connected by a coupling 39 (see Figs. 5 and 14) to a shaft 40 which is supported by a housing 41 which is secured to the side of the housing 33 which, as before stated, supports the shaft 30 and is secured to the rear side of the annulus 24. This shaft 40 is connected by three gears 42, 42a and 42b to a shaft 43 extending into the housing 33, the said gears being of a variable ratio to suit different driving speeds of the chuck operating member and being of variable diameters to permit different displacements of shafts 40 and 43 to accommodate chucks of different sizes and to admit of the unit, including the housing 33, to be moved inward or outward in accordance with the size of the chuck.

The shaft 43 is provided on its inner end within the housing 33 with a bevel pinion 44 which meshes with a bevel gear 45 forming one element of a slipping clutch which is clearly illustrated in Figs. 4 and 14. This slipping clutch is arranged on a shaft 46 and consists, in addition to the bevel gear 45 which may rotate freely on shaft 46, of a friction clutch member 47 which is held in engagement with the gear 45 under predetermined pressure by a coil spring 48 surrounding a portion of the shaft 46 and engaging an adjustable abutment in the form of a nut 49 secured onto shaft 46, the clutch member 47 being keyed to shaft 46 but slideable thereon. This slipping clutch located in the drive between the headstock and the shaft carrying the chuck closing and opening member is to determine the pressure with which the jaws engage or grip the work piece and, secondarily, it prevents breakage when the transmitted load reaches a predetermined amount at which time the clutch will slip. It will be understood that the load which is transmitted will depend upon the nature or size of the work and is determined by the adjustment of the nut 49.

On shaft 46 is provided a pinion 50 engaging a wide faced pinion 51 on a shaft 52 supported by the housing 33. From this pinion and shaft 52 power is transmitted to shaft 30 to rotate the same in opposite directions through two clutch gears 53 and 54 which are supported in the housing 33 and have sleeve-like extensions which form supports for shaft 30. The drive takes place direct from pinion 51 to clutch gear 53 to rotate the shaft 30 in one direction and the drive from pinion 51 to clutch gear 54 for rotating shaft 30 is through two idler gears 55 and 56 (see Fig. 14) on a shaft 57 also supported by the housing 33, the idler gear 56 engaging the clutch gear 54.

Either clutch gear 53 or 54 may be clutched to the shaft 30 by a movable clutch member 57 which is splined to shaft 30 so as to rotate therewith and is adapted to be shifted lengthwise thereof between the clutch gears

53 and 54 by a shifting lever 58 (see Figs. 4 and 10), which is operated as will be explained presently. It might be here stated that the clutch gears and the opposite ends of 5 the clutch member 57 are provided with clutch teeth which come into engagement so as to transmit motion from one or the other of the clutch gears to the clutch member 57, the teeth being spaced apart so that a hammer 10 blow will be imparted to the clutch member and therefore to the shaft 30, this being of especial importance in the opening operation, and it is useful also in the closing operation when an exceptionally strong gripping is desired. 15

The shaft 30 is adapted to be moved in an endwise direction, in which event it slides through the clutch gears 53 and 54 and movable clutch member 57, by means of a 20 shifting lever 59 (see Figs. 4, 6 and 7) having shoes engaging a shoe ring 60 formed on the shaft. The manner in which this lever 59 is controlled and shifted will also be explained presently.

25 The main control lever which controls the rotation of the work spindle and chuck in both directions is shown at 61, this lever being arranged as is usually the case on top of the headstock and projecting forwardly so

30 that it can be conveniently reached by the operator in front of the machine. In Fig. 3 the lever is shown in its neutral position, and to cause the work spindle and chuck to be rotated in one direction it is swung from

35 neutral position in one direction and vice versa. This main control lever controls a main control clutch including a movable clutch member designated by the reference character 62 in Fig. 14, which clutch mem-

40 ber is shown on a clutch shifting member 62a provided with a shoe ring 62b which is adapted to be moved back and forth by a lever 62c (see Fig. 13) as the main control lever is rocked. This lever is connected to

45 a vertical rock shaft 62d to which the main control lever 61 is connected. This clutch member 62 is adapted to clutch either of two gears 63 and 64 to a shaft 65, the gears 63 and 64 being rotated in opposite direc-

50 tions by the constant speed gear 34 through gears 34a, indicated in Fig. 14. In this instance the shaft 65 carries a sliding gear cone 66 by which any one of a plurality of speeds may be imparted to the work spindle

55 22 which is provided with gears adapted to engage the gears of the cone. It will be understood that we have not attempted to indicate all of the gears and shafting employed in the usual headstock but the show-

60 ing of Fig. 14 will indicate a suitable driving connection between the main source of power, in this case the pulley 32, and the work spindle for rotating the latter and the chuck in opposite directions.

65 The chuck closing and opening mechanism

is controlled by a lever 67 which is also on the front side of the machine and which, like the lever 61, is supported on the top of the headstock. This lever 67 is capable of two distinct movements, one being a swinging movement in a plane at right angles to the axis of the machine and the other being a rocking movement in a plane parallel to the axis of the machine. The functions of these movements will be explained presently.

70 For the swinging movement, this lever is pivoted at 68 on a bracket 69 which is capable of rotating to permit the rocking movement of the lever. This bracket 69 is rotatably supported on the substantially tubular portion 70 of a support 71 which is attached to the top of the headstock, this support consisting of an irregularly shaped casting as will be seen from Figs. 8 and 9. The upper end of the lever 67 is pivoted to a

80 shaft 72 which is given an endwise movement when the lever 67 is swung on the pivotal axis 68 and is given a rocking movement when the lever is rocked by rotating the bracket 69. This shaft extends across the

85 top of the headstock and at its rear end it is provided with a pinion 73 and just forwardly of the pinion it is provided with annular teeth or a circular rack 74. When the lever 67 is swung from neutral position out-

90 wardly, the shaft 72 moves inwardly and the effect of this is first to rock a bell-crank 75 having at one end teeth engaging the circular rack 74 and the movement of this bell-crank shifts a rack 76. The second and

95 later effect of the rearward movement of shaft 72 is to move the pinion into further engagement with a second rack 77. These two racks are supported in horizontal position, in the rear end of the supporting mem-

100 ber 71 (see Fig. 8) and in an upwardly projecting member 33a forming an extension of the housing 33. When the rack 76 is shifted, it rocks a lever 78 which is fixed to the

105 top of a vertical shaft 79 (Fig. 8) contained within a portion of the housing 33 and provided near its lower end with the lever 59 (see Figs. 6 and 7) which is utilized in shifting shaft 30 in an endwise direction to bring

110 the chuck operating member into or out of engagement with the jaw shifting part or parts of the chuck. The function of the pinion 73 which is at all times in mesh with the second rack 77 is to shift the clutch member

115 57 the pinion being rotated by rocking the lever 67 and bracket 69 thus turning the shaft 72 and the pinion 73. The endwise movement imparted to the rack 77 by the pinion 73 shifts a lever 80 secured to the top of a

120 second vertical shaft 81 which, like the shaft 79, is within a portion of the housing 33. Near the lower end of vertical shaft 81 is the clutch shifting lever 58. As previously explained, the direction in which shaft

125 30 is rotated depends upon the direction in

which the clutch member 57 is shifted, and, as will be apparent, the clutch member may be caused to engage either clutch gear 53 or 54, depending upon the direction in which the rack 77 is shifted, and this in turn depends upon the direction in which the control lever 67 is rocked.

It is of vital importance in order that breakage may be avoided, that the chuck closing and opening member be in full engagement with the jaw shifting part of parts of the chuck before this member is permitted to rotate. Accordingly, it is important and vital to the success of the power operated chuck closing and opening mechanism that the shaft 30 be given its full endwise movement to engage the chuck operating member with the jaw shifting member or members of the chuck before the shaft is rotated and that it be held in the engaged position and be prevented from accidentally or otherwise being moved out of engagement while the shaft is being rotated in either direction. This makes necessary the provision of means for requiring the full swinging movement of the control lever 67 away from neutral position before it can be rocked in either direction, and after the chuck has been closed, the completion of the rocking movement to place the clutch member 57 in neutral position before shaft 30 is retracted. This is accomplished in a simple but very effective manner by providing on the endwise movable and rocking shaft 72 a pin 82 which engages in a T-slot 83 formed in a portion of the support 71. When the control lever 67 is in neutral position, the pin occupies the position in the slot shown in Figs. 3, 8 and 12 being at the front end of that portion of the slot which stands transversely to the axis of the machine. When the lever 67 is swung outwardly its full distance this pin is brought into line with that portion of the slot which extends longitudinally of the axis of the machine, and, accordingly, when the pin occupies this position and not until then can the lever be rocked to cause the shaft 30 to be rotated in one direction or the other, the pin being shown in this position in Fig. 11 and in Fig. 12 at 82a where its position at such time is shown by dotted lines. When the pin has been moved to position 82a by the endwise movement of the shaft 73 resulting in the endwise movement of shaft 30 to cause the engagement of the chuck operating member with the chuck, it (the pin) may then be moved to either end of the slot to position 82b or 82c shown in Fig. 12, when shaft 72 is rocked to engage the clutch member 57 with one or the other of the clutch gears 53 and 54, it being understood that when the pin is in position 82b, the clutch member 57 is in engagement with one clutch gear and when it is in position 82c, the clutch member is in engagement with the other

clutch gear. It follows also that after the chuck has been closed or opened the pin must be brought back into alignment with the transversely extending portion of the slot resulting in the disengagement of the clutch member 57 from the clutch gear which it previously engaged and then the pin may be moved forward to its normal position which is done by swinging the control lever forwardly to its normal position indicated in Fig. 9.

When the control lever 67 is in its normal inoperative position, it is highly desirable that the clutch member 57 be maintained in its neutral position and that it be prevented from shifting accidentally or otherwise into engagement with either of the clutch gears 53 or 54. This desirable feature is attained by our construction because of the constant engagement of the pinion 73 with the teeth of the rack 77 for the reason that the shaft 73 is held from rotating by the engagement of the pin 82 with the transverse portion of the T-slot 83 (the clutch member 57 at such time being in neutral position, as previously explained). In brief, the pinion 73 is at this time locked against rotary movement and the engagement of the pinion with the rack locks the latter against endwise movement and thus the shifting of the clutch member 57 is prevented.

In addition to the parts described above, we have provided as a part of our improved mechanism a brake for checking the rotation of the work spindle and chuck as soon as the lever 61 is thrown from either operative position to neutral position thus permitting the operator to open the chuck by operating the control lever as soon as a work piece has been completed, thereby avoiding loss of time which would otherwise be caused by the inertia of the rotating parts. Additionally, we provide for the automatic application of the brake and for the disengagement of the brake member from the chuck by the mere throwing of the lever 61, and we also provide an interlock between the main control lever 61 and the lever 67 which controls the chuck closing and opening mechanism so that it will be impossible for the operator to attempt to open or close the chuck by inserting the chuck operating member on shaft 30 into the chuck while the chuck is rotating, and also impossible for the operator to start the work spindle and chuck in rotation when the chuck operating member is engaged with the chuck either during the chuck closing or opening operation. Thus liability of breakage is avoided. In the accomplishment of these ends there is provided in the supporting member 71 a horizontally arranged shaft 84 on which is mounted for slight rocking movement a wide faced lever 85 which extends substantially horizontally toward the front side of the machine. Addi-

tionally, there is pinned or otherwise secured to this shaft a collar 86 having a forwardly projecting tongue 87 which is adapted to engage the lower end of an adjustable set screw 88 which is carried by the lever 85 a short distance forwardly of the shaft 34. Additionally, there is pinned or otherwise secured, in this instance, to one end of shaft 34 a lever 89 which extends from the shaft 34 toward the rear side of the machine and carries a brake shoe 90 which in turn is adapted to engage a grooved portion 91 of the chuck body, this grooved portion being arranged adjacent the rear end of the chuck as shown in Fig. 3.

The brake shoe is preferably pivotally connected to lever 89 by a pin 92 so that it may be adjusted to conform to the contour of the shoe engaging portion 91 of the chuck body. In this instance the shoe may be rocked about the pin 92 and held in any desired position of adjustment by a pair of set screws 93 extending through the lever and engaging the shoe near its opposite ends. The brake shoe is normally pressed against the shoe engaging portion 91 of the chuck body by means of a spring 94 arranged between the top of the lever and an adjustable abutment 95 carried by a screw 96 mounted in an ear 97 forming a part of the support 71. With this arrangement the action of the spring 94 is to normally tend to seat the brake shoe against the shoe engaging portion 91 of the chuck body and at the same time to elevate to its uppermost position, the wide faced lever 85 through the medium of the lip 87 and set screw 88. Obviously by adjusting the set screw 88 it is possible to adjust the relative positions of the brake shoe lever 89 and the wide faced lever 85, which adjustment may be advisable from time to time as wear on the brake shoe occurs.

It will be observed that the lever 61 may be swung from neutral position shown in Fig. 3 in either direction to cause the work spindle and chuck to be rotated in either forward or reverse direction, this swinging movement of the lever taking place between two elevated portions 71a of the supporting member 71 which portions are bridged by a cross-plate 98 serving as a guide plate for the lever 61, this plate extending immediately over the lever 61 as illustrated in Figs. 1 and 3 but removed from Fig. 8, the upper side of the lever being at all times in contact with the lower face of this plate. The lower side of the lever 61 is given a V-shape for a portion of its length, as best shown at 61a, in Figs. 1, 9 and 11, and this V-shaped portion of the under side of the lever is adapted to engage in a V-shaped notch 99 formed on the upper side of the wide faced lever 85, this engagement taking place only when the lever is in neutral position. It will be observed that the front end of the wide faced lever 85 has an

extension 100, one end of which projects over a portion of the T-slot 83 (see Fig. 8), which is engaged by the pin 82 carried by the shaft 72 connected with the control lever 67, this extension being preferably in the form of a hardened plate attached to lever 85.

When the main control lever 61 is in neutral position so that the V-shaped lower portion 61a thereof is directly in line with the slot 99 provided in the wide faced lever 85, the brake shoe 90 is engaged and the lever is held by the spring 94 in its upwardmost position (see Fig. 11). At this time the extension 100 at the forward end of the lever lies above the pin 82 in the T-slot, this permitting the pin to be moved under it, i. e., permitting free or unrestrained movement of the pin and, therefore, free or unrestrained movement of the control lever 67 for the chuck opening and closing mechanism. When the pin 82 is moved beneath the extension 100 of the wide faced lever 85, as shown in Fig. 11 at 82a, it is obvious that the lever 85 cannot be depressed by movement of the main control lever 61.

When the pin 82 is in its normal position at the forward end of the T-slot, i. e., out from beneath the extension 100 of the lever 85, and when the main control lever 61 is swung in either direction from neutral position as shown in Figs. 1 and 9, the V-shaped portion of the lever of course rides out of the V-shaped notch 99 of the lever 85 and this cams the lever 85 downwardly, lifting the brake shoe from the shoe engaging portion 91 of the chuck body and it will be apparent that as long as the lever 61 is out of neutral position the brake shoe will be held out of engagement with the shoe engaging portion of the chuck body. When the lever 61 is swung from neutral position, as just explained, thus causing the spindle and chuck to be rotated in one direction or another (depending of course upon which direction the main control lever has been swung from neutral position) the extension 100 of the lever 85 is by such movement of the lever cammed downward so as to lie immediately behind the pin 82, as best shown in Fig. 9, so that as long as the lever is out of neutral position it will be impossible for the operator to shift the control lever 67 to throw into operation the chuck closing and opening mechanism.

As previously stated, if the pin 82 is beneath the extension of the lever 85, it is impossible for the operator to shift the main control lever 61 from neutral position and thus impossible for him to start the work spindle and chuck into operation and to lift the brake from the chuck body as long as the chuck opening and closing mechanism is in operation or as long as the chuck operating member of this mechanism is in engagement with the chuck. In fact, with our improved mechanism it is impossible to shift the main control lever from

its neutral position until the chuck operating member on shaft 30 is withdrawn to its normal position in which event the control lever 67 is in neutral position and the pin 82 is in the forwardmost portion of the T-slot. It will be seen therefore that by this mechanism complete safety is provided.

While we have shown the preferred construction, we do not desire to be confined to the precise details shown but aim in our claims to cover all modifications which do not involve a departure from the spirit and scope of our invention.

Having thus described our invention, we claim:

1. A machine tool having a driven member for rotating the work, a driving member for rotating the driven member in opposite directions, a brake for checking the rotation of said driven member and engaging the same, a control member for controlling the rotation of the driving member in both directions and movable in either direction from neutral position, and a connection between the control member and said brake arranged to cause the brake to be released when the control member is moved from neutral position to operative position in either direction and to be applied when the control member is moved back to neutral position.

2. In combination with a machine tool having a headstock containing a spindle adapted to be rotated in either direction, a chuck mounted on the spindle, a brake arranged to engage a portion of the chuck, a control lever for controlling the rotation of the spindle and movable from normal inoperative position in either direction, and a connection between the control lever and the brake whereby the brake is automatically applied when the control lever is moved to normal position and is released from the chuck when the lever is moved from normal position in either direction.

3. In combination with a machine tool having a headstock provided with a spindle adapted to be rotated in either direction, a lever movable in either direction from normal position to control the rotation of the spindle, a chuck on the spindle, a brake member engageable with a portion of the chuck, and means associated with the brake member normally urging it into engagement therewith, and a connection between the control lever and the brake member whereby the brake member is released from the chuck when the lever is moved in either direction from normal position and is automatically restored to braking position when the lever is moved in either direction from normal position.

4. In combination with a work holder having means for engaging a work piece, power means for shifting the work engaging means and including a rotatable member movable toward and from the work holder, and a control member movable in one direction to cause

said rotatable member to engage the work holder and movable in another direction to cause its rotation to shift the work engaging means.

5. In combination with a work holder having work engaging means, power means for shifting the work engaging means and including a rotatable member movable into and out of engagement with the work holder, and a control member movable in an endwise direction to cause the engagement of said device with the work holder and rotatable to cause said member to be rotated to actuate the work engaging means.

6. The combination with a work holder having work engaging means, of power means for shifting the work engaging means and including a member rotatable in either direction and movable into and out of engagement with the work holder, and a control member mounted for movement in an endwise direction to cause said first named member to engage or disengage the work holder and rotatable in either direction to cause said member to be rotated to shift the work engaging means.

7. In combination with a rotatable work holder having work engaging means, a drive for said work holder, a control member for the drive by which the rotation of the work holder may be started and stopped, means for shifting the work engaging means and including a rotatable member movable into and out of engagement with the work holder, a control member movable to shift said rotatable member relative to the work holder and to control its rotation, and an interlock between the two control members.

8. In combination with a rotatable work holder having work engaging means, a drive for said work holder, a control member for the drive, means for shifting the work engaging means and including a rotatable member movable into and out of engagement with the work holder, a control member for causing said device to be moved relative to the work holder and to be rotated, and an interlock between said control members so as to prevent the engagement between said rotatable member and the work holder unless the first mentioned control member is in inoperative position.

9. In combination with a rotatable work holder having work engaging means, a drive for said holder, a control member for the drive having operative and inoperative positions, means for shifting the work engaging means of the work holder and including a rotatable member movable into and out of engagement with the work holder, a drive therefor, a control member for controlling both the rotation of said rotatable member and its movement toward and from the work holder, and an interlock between said control members which prevents the operation of the first control

member unless the second control member is in neutral position.

10. In combination with a rotatable work holder having work engaging means, a drive for said holder, a control member for the drive having operative and inoperative positions, means for shifting the work engaging means of the work holder and including a rotatable member movable into and out of engagement with the work holder, a drive therefor, a control member for controlling both the rotation of said rotatable member and its movement toward and from the work holder, and an interlock between said control member which prevents the operation of the first control member unless the second control member is in neutral position and prevents the operation of the second control member unless the first control member is in inoperative position.

11. In combination with a rotatable work holder having work engaging means, a brake for checking the movement of the work holder, a drive for the work holder, a control member for said drive and brake, and means for shifting the work engaging means of the work holder and having a control member interconnected with said first named control member.

12. In combination with a rotatable work holder having work engaging means, a power drive for the work holder, a brake for checking the rotation of the work holder, a control member controlling both the power drive and the brake, means for shifting the work engaging means and including a rotatable member movable toward and from the work holder, a control member movable in two directions to control the engagement of said rotatable member with the work holder and also its rotation, and means forming an interlock between said control members.

13. In combination with a work holder having work engaging means, means for shifting the work engaging means and including a rotatable member movable toward and from the work holder, and a control member arranged so that when first moved in an endwise direction it will shift said member into engagement with the work holder and when then rocked it will cause the rotation of said member.

14. In combination with a work holder having work engaging means, means for shifting the work engaging means and including a rotatable member movable toward and from the work holder, a control member movable in an endwise direction to cause said member to be moved into engagement with the work holder and capable of a rocking movement to cause said member to be rotated, and means by which the control member is constrained to be first moved endwise before being rocked for the work engaging operation.

15. A machine tool having a head provided

with a work spindle adapted to be provided with a work holder having work engaging means, a drive in said head for the spindle and work holder, and power means for shifting the work engaging means, said power means including driving means and a member arranged laterally of and movable substantially horizontally relative to said driving means into and out of engagement with the work holder.

16. A machine tool having a head provided with a work spindle, a drive for the spindle, a chuck adapted to be applied to the spindle, power means for closing and opening the chuck and including a drive engageable with an element in the head and including also a member movable laterally on the rear side of the head toward and from the periphery of the chuck.

17. The combination with a work holder having work engaging means, means for shifting the work engaging means and including an operating member movable toward and from the work holder and also rotatable, a control member capable of two separate movements, one to cause the operating member to be moved into or out of engagement with the work holder and the other to control the rotation of said operating member, and devices between the control member and the operating member which are separately actuated by the two movements of the control member.

18. In combination with a work holder having work engaging means, means for shifting the work engaging means and including an operating member movable endwise toward and from the work holder and rotatable in either direction, a clutch for controlling its rotation, a control member having two separate movements, a shifting means between said control member and the operating member to cause the endwise movement of the operating member during one movement of the control member, and shifting means between the control member and the clutch to cause the clutch to be shifted during the other movement of the control member.

19. In combination with a work holder having work engaging means, means for shifting the work engaging means and including an operating member movable in an endwise direction toward and from the work holder and rotatable, a clutch for controlling its rotation, a shifter for moving the operating member endwise, a control member having two separate movements one for the endwise movement and one to control the rotation of the operating member, and operating means between said control member and the shifter and between said control member and the clutch.

20. In combination with a work holder having work engaging means, means for

shifting the work engaging means and including an operating member movable in an endwise direction toward and from the work holder and rotatable, a clutch for controlling 5 its rotation, a shifter for moving the operating member endwise, a control member having two separate movements one for the endwise movement and one to control the rotation of the operating member, and operating 10 means between said control member and the shifter and between said control member and the clutch, said operating means comprising a pair of racks, one actuated by one movement of the control member and the other actuated by another movement of the 15 control member.

21. In combination with a work holder having work engaging means, means for shifting the work engaging means and including 20 an operating member movable toward and away from the work holder and also rotatable, a shifter for moving the operating member toward and from the work holder, a clutch for controlling the rotation 25 of the operating member, a control member having two separate movements, means for constraining the control member so that the part controlled by one movement is locked against movement until the part controlled 30 by the other movement is shifted.

22. In combination with a work holder having means for engaging a work piece, means for shifting the work engaging means and including an operating member movable toward and from the work holder and also rotatable, means comprising a control member 35 movable in two directions to cause the operating member to be moved toward or from the work holder and to control its rotation, and means for preventing the movement of the control member in one direction until its movement in the other direction is completed.

23. In combination with a work holder having means for engaging a work piece, 40 means for shifting the work engaging means and including an operating member capable of a plurality of movements, means comprising a control member for controlling said movements, and means constraining said control member to cause one movement to be completed before another is initiated.

24. In combination with a work holder having means for engaging a work piece, means for shifting the work engaging means and including an operating member movable 45 in different directions, means comprising a control member for controlling said movements, and means for preventing both movements being imparted at the same time to the operating member by the control member.

25. In combination with a work holder having means for engaging a work piece, means for shifting the work engaging means and including an operating member, a shifter 50 for moving the operating member toward

and from the work holder, means comprising a clutch for causing the operating member to be rotated, a control member operatively connected with the shifter and clutch, and means for preventing the shifter and clutch being 70 both operated at the same time.

26. In combination with a work holder having means for engaging a work piece, means for shifting the work engaging means and including an operating member, a shifter for moving the operating member toward and from the work holder, means comprising a 75 clutch for causing the operating member to be rotated, a control member operatively connected with the shifter and clutch, and means for preventing the operation of the clutch until the shifter has been moved to cause the operating member to engage the work holder to actuate the work engaging means.

27. In combination with a work holder having means for engaging a work piece, means for shifting the work engaging means and including an operating member, a shifter for moving the operating member toward and from the work holder, means comprising a 80 clutch for causing the operating member to be rotated, a control member operatively connected with the shifter and clutch, and means for preventing the movement of the shifter to disengage the operating member from the 85 work holder before the clutch has been disengaged.

28. In combination with a work holder having work engaging means, power means for shifting the work engaging means, including 90 an operating member movable into and out of engagement with the work holder and also rotatable, a single control member for controlling both movements of the operating member, a shifter and a clutch for said control member operatively connected with the control member, and means for preventing the engagement of the clutch when the control member is in inoperative position.

29. In combination with a work holder having work engaging means, means for shifting the work gripping means and including an operating member movable toward and from the work holder and also rotatable, a shifter and a clutch for imparting the 100 movements to the operating member, a control member having two separate movements, one for the shifter and the other for the clutch, a pair of endwise movable members between the control member and the shifter and clutch respectively, and means connecting the control member with said endwise movable members.

30. In combination with a work holder having work engaging means, means for shifting the work engaging means and including an operating member movable toward and from the work holder and also rotatable, a shifter and a clutch for imparting 105 the movements to the operating member,

130

a control member having two separate movements, one for the shifter and the other for the clutch, a pair of actuating members between the control member and the clutch respectively, and means connecting the control member with one of said actuating members, said means including a pinion on the control member.

31. In combination with a work holder having work engaging means, means for shifting the work engaging means and including an operating member movable toward and from the work holder and also rotatable, a shifter and a clutch for imparting the movements to the operating member, a control member having two separate movements, one for the shifter and the other for the clutch, a pair of actuating members between the control member and the clutch respectively, and means connecting the control member with one of said actuating members, said means including a rack on the control member.

32. In combination with a work holder having work engaging means, means for shifting the work engaging means and including an operating member movable toward and from the work holder and also rotatable, a shifter and a clutch for imparting the movements to the operating member, a control member having two separate movements, one for the shifter and the other for the clutch, a pair of actuating members between the control member and the shifter and clutch respectively, and means connecting the control member with said actuating members, said means including a circular rack and a pinion on the control member.

33. In combination with a work holder having means for engaging a work piece, power means for shifting the work engaging means and including an operating member having a plurality of separate movements, one for engaging the work holder, and one for actuating the work engaging means, and a single control member for causing said movements to be imparted to the operating member.

34. In combination with a work holder having work engaging means, means for shifting the work engaging means including an operating member having a plurality of separate movements, one for engaging the work holder, and one for actuating the work engaging means, and a single member for controlling said movements so as to cause them to be imparted successively.

35. A machine tool having a head provided with a work spindle and a drive for the spindle, a chuck on the spindle, power means for closing and opening the chuck including a member movable laterally on the rear side of the head toward and from the periphery of the chuck and a control member therefor at the front side of the head.

36. A machine tool having a driven member including a chuck, a driving member for rotating said driven member in opposite directions, a brake for checking the rotation of said driven member and chuck and adapted to engage said chuck, a control member for controlling the rotation of the driving member in opposite directions and movable in either direction from neutral position, and a connection between the control member and said brake arranged to cause the brake to be released when the control member is moved from neutral position to operative position in either direction and to be applied when the control member is moved back to neutral position.

In testimony whereof, we hereunto affix our signatures.

EDWARD P. BURRELL.
FRED H. BOGART.
